GYROSCOPIC INSTRUMENT

Waldemar Möller, Rechlin, near Mirow, Germany,
assignor to Askania-Werke A. G. vormals Central
Werkstatt Dessau und Carl Bamberg-
Friedenau, a German company

Application September 21, 1936, Serial No. 101,868
In Germany September 26, 1935

8 Claims. (Cl. 33—204)

This invention relates to improvements in air-driven gyroscopes which are equipped with a pneumatic positional pick-off for operating a remote indicator or an automatic steering device. 5 The invention relates further to an improved method of operating said gyroscopic apparatus.

One object of this invention is to greatly reduce the quantity of air required for operating the instrument by a novel method which consists in using the same air twice for driving the gyroscope and also for operating the positional pick-off.

The invention further aims to reduce the size and weight of the air pressure generating plant 15 and consequently the source of power for driving the same. This is an important consideration in connection with apparatus designed for use on aircraft where a saving of weight, space and power is essential.

20 The invention further aims to increase the reliability of the gyroscopic instrument by passing a smaller quantity of air through the same, thereby reducing the quantity of dust and moisture which decreases the life and dependability 25 of the instrument.

The invention further aims to provide means for using air of comparatively high pressure without employing special power consuming reduction valves for reducing the high pressure 30 required for driving the gyroscope to a relatively low pressure required by the pick-off.

Other objects and advantages will appear more fully hereinafter from a consideration of the detailed description which follows, together with 35 the accompanying drawings, wherein embodiments of the invention are illustrated. It is to be understood, however, that the drawings are for the purpose of illustration only and not designed as a definition of the limits of the present 40 invention, reference for this purpose being had to the accompanying claims.

Fig. 1 is a sectional elevation of a directional gyroscope equipped with a positional pick-off for movements about the vertical axis;

45 Fig. 2 is a top plan view of the instrument shown in Fig. 1, a part being removed;

Figs. 3 to 7 are simplified diagrammatic views of different modified forms of the invention.

In Fig. 1, the invention is shown as applied to 50 a directional gyroscope, but it is understood that the invention may also be applied to artificial horizons, turn indicator gyroscopes and the like. In this example, a gyro rotor 11 spins about a horizontal axis 12 in the rotor bearing member 55 or frame 13 which, in turn, is pivoted in hori-

zontal pivots 14, 15 at right angles to the rotor spin axis in a vertical frame 16. The vertical frame is rotatable in vertical bearings 17, 18 in an air-tight casing 19. The vertical frame is shown as provided with a compass-card 20 visible through the window 21 of the casing. 5

Compressed air is supplied to the instrument through the pipe-coupling 22 and passes through the conduit 23 into a hollow space 24 and through holes 25, 26 into another hollow space or 10 chamber 27. From the latter chamber the air passes through a tube 28 to one or several nozzles 29 in the part 30 secured to said tube 28. From the nozzle or nozzles, the air is discharged 15 against the rotor 11 which is shown as being provided with cups or blades 31.

The relatively high pressure of the air entering 20 at 22 is greatly reduced by the expansion at the nozzle 29 and by imparting a part of its energy to the rotor.

The used air leaves the casing through openings 32, 33 and enters two conduits or pipes 34, 35 which are shown as being provided with constrictions 36, 37. The air leaves the said conduits or pipes 34, 35 through openings 38, 39. At a 25 close distance from the openings, there is provided a disk 40 preferably of circular shape and rigidly mounted eccentrically on an extension or shaft 41 of the vertical frame 16 so that it rotates with the frame. The disk, however, may 30 have any other suitable form. The conduits or pipes 34, 35 are shown as being mounted on a supporting member 42 which is rotatable in an annular recess 43 formed by an annular ring 44 on the casing 19. The supporting member may 35 be rotated with respect to the casing 19 by means of a worm 45 meshing with a worm wheel 46 integral with or secured to the supporting member 42. The pipes or conduits 34, 35 are shown as being connected with flexible pipes 49, 50, connected at 47, 48 to the conduits and extending through openings in the supporting member 42. The hose or pipes 49, 50 connect the interior 40 space of the said conduits or pipes 34, 35 with the chambers 51, 52 of a diaphragm casing 53. 45 Instead of the diaphragm casing 53, other suitable devices responsive to differential pressure may be employed. The diaphragm 54 in casing 53 is shown as being connected to a pointer 55, it being understood that the diaphragm may also 50 be connected to operate an automatic steering mechanism in a well known manner.

Upon relative turning of the casing, together with the pipes or conduits 34, 35 and the vertical frame 16 which carries the disk 40, the latter 55

will oppositely open and close the openings 38, 39, thereby varying the pressure in the interior of the said pipes or conduits and operating the diaphragm 54 and pointer 55. The air leaving the openings 38, 39 will leave the interior of the supporting member 42 having the form of a casting through the holes 56 in the top 57 of the same and escape into the atmosphere.

In the following diagrams, Figs. 3 to 7, the mechanical structure of the instrument is indicated by simple lines only for the sake of illustrating the air passages more clearly. The structural details of the instruments in Figs. 3 to 7 will be clear to anyone skilled in the art.

Fig. 3 shows a modified form of the invention which is similar to the form in Fig. 1. In this modification, the outlets 36, 37 for the discharging air are restricted and constant, while the inlets 38, 39 are variable by the controlling disk 40. The conduits 49, 50 connect the pick-off with the differential pressure responsive device. An additional shielding disk 60 may be provided to prevent turbulent air from setting up a false pressure differential in the pipes or conduits 34, 35.

Fig. 4 shows a modified form of the invention in which air is continuously withdrawn from the casing through conduit 70 by means of a suitable pump 71. Air enters the instrument through the openings 72, passes through the variable openings 38, 39 controlled by the relative position of the pipes 34, 35 and the disk 40, and reaches the chamber 73 through the non-variable constrictions 36, 37. Through the openings 74, 75 the air enters the pipe 28 bearing the nozzle 29.

It appears that, due to the different cross sectional area of the nozzle 29 and the pick-off passages 34, 35, the greater pressure drop will again be at the driving nozzle 29, similar to the compressed air operated devices shown in Figs. 1 to 3, where the air of high pressure expands at the driving nozzle and passes through the pick-off at relatively low pressure.

Fig. 5 shows a modified form of the apparatus shown in Fig. 4 with non-variable inlet 36, 37 and variable outlets 38, 39, and disc 40, similar to the form shown in Fig. 3.

Fig. 6 shows another modified form of the invention. The pick-off used in this instrument is shown and described in the patent to Wunsch No. 1,729,850, dated Oct. 1, 1929. In this form compressed air enters at 23, passes through the pipe 28 and drives the rotor when leaving the nozzle at 29. The used air leaves the casing through the nozzles 80, 81 of the pick-off. The jets emerging from the nozzles 80, 81 will partially enter the opposite pair of nozzles 82, 83 depending upon the relative position of the disk 40 and the nozzles and set up a differential pressure in the conduits 49, 50. The air will finally leave the pick-off casing through the opening 84 into the atmosphere.

Fig. 7 shows the instrument of Fig. 6 in some-what modified form for vacuum operation. Air at atmospheric pressure enters the pick-off casing through conduits 80', 81'. A differential pressure will be set up in conduits 49, 50 having nozzles 82, 83 opposite to the nozzles 80, 81' controlled by the disk 40. The air further passes through the opening 85 and the pipe 28 to the driving nozzle and is withdrawn from the gyro casing at 70.

The present embodiments of this invention are to be considered in all respects as illustrative and not restrictive, reference being had to

the appended claims, rather than to the foregoing description to indicate the scope of the invention.

What is claimed is:

1. In combination with a gyroscope having a casing, a rotor therein; air jet means for driving said rotor; a rotor bearing member; means for supporting said member in said casing for movement about an axis at an angle to the rotor spin axis; and differential air flow means actuated by relative turning of said rotor bearing member and casing about said supporting axis, said air jet means and differential air flow means being arranged to be operated in succession by the same air. 15

2. In combination with a gyroscope having a casing, a rotor therein; air jet means for driving said rotor; a rotor bearing member; means for supporting said member in said casing for movement about an axis at an angle to the rotor spin axis; differential air flow means actuated by relative turning of said rotor bearing member and casing about said supporting axis, and said differential air flow means discharging into the atmosphere and actuated by the air which spins the rotor as it discharges through said air flow means. 20

3. In combination with a gyroscope having a casing; a rotor therein; air pressure means for driving said rotor; a rotor bearing member; means for supporting said member in said casing for movement about an axis at an angle to the rotor spin axis; and a positional pick-off including discharge conduits connecting the interior of the gyroscope casing with the atmosphere; and means controlled by relative turning of said rotor bearing member and casing about said supporting axis for varying the discharge of air through the said conduits. 25 35

4. In combination with a gyroscope having a casing; a rotor therein; air pressure means for driving said rotor; a rotor bearing member; means for supporting said member in said casing for movement about an axis at an angle to the rotor spin axis; and a positional pick-off including discharge conduits connecting the interior of the gyroscope casing with the atmosphere; a constriction in each of said conduits; and means controlled by relative turning of said rotor bearing member and casing about said supporting axis for differentially varying the relative discharge of air through the said conduits, whereby a differential pressure is set up in the said conduits between the said constrictions and the said means for varying the discharge of air. 40 45 50 55

5. In combination with a gyroscope having a casing; means to create vacuum pressure in said casing; a gyro rotor in said casing; a rotor bearing member; means for supporting said member in said casing for movement about an axis at an angle to the rotor spin axis; a driving nozzle for spinning the rotor; means for admitting atmospheric air to said driving nozzle including conduits therefrom opening to the atmosphere; and means controlled by relative turning of said rotor bearing member and casing about said supporting axis for varying the opening of said conduits whereby a differential air flow is set up in the same. 60 65

6. In combination with a gyroscope having a casing; means to create vacuum pressure in said casing; a gyro rotor in said casing; a rotor bearing member; means for supporting said member in said casing for movement about an axis at an angle to the rotor spin axis; a driving nozzle for 70 75

spinning said rotor; means for admitting atmospheric air to said nozzle, said means including two conduits, a constriction in each of the conduits and means controlled by the relative turning of said rotor bearing member and casing about said supporting axis for differentially varying the flow of air through said conduits whereby a differential pressure is set up in the said conduits between the constrictions and the said 10 means for varying the flow of air.

7. In combination with a gyroscope having a casing; a rotor therein; air pressure means for driving said rotor; a rotor bearing member; means for supporting said member in said casing 15 for movement about an axis at an angle to the rotor spin axis; a pair of nozzles communicating with the interior of said casing and permitting air to discharge from the same; a second pair of nozzles positioned oppositely to the first pair of 20 nozzles; and a disk actuated by relative turning of said rotor bearing member and casing about said supporting axis for differentially intercepting the air jets emitted from the said first pair

of nozzles thereby varying the pressure set up in the said second pair of nozzles.

8. In combination with a gyroscope having a casing; means to create vacuum pressure in said casing; a gyro rotor in said casing; a rotor bearing member; means for supporting said member in said casing for movement about an axis at an angle to the rotor spin axis; a second casing; a driving nozzle for spinning the rotor; a conduit connecting the said driving nozzle with the interior of said second casing; a pair of nozzles in said second casing; means to admit atmospheric air to said pair of nozzles; a second pair of nozzles each positioned oppositely to a respective one of said first pair of nozzles in said second casing; 15 and a disk controlled by relative turning of said rotor bearing member and casing about said supporting axis for differentially intercepting the air jets emitted from the said first pair of nozzles thereby varying the pressure set up in the said 20 second pair of nozzles.

WALDEMAR MÖLLER.
